FLUORESCENT ELECTRIC LAMP

Henry J. McCarthy, Danvers, Mass., assignor to
 Sylvania Electric Products Inc., a corporation of
 Massachusetts

Application September 13, 1941, Serial No. 410,720

1 Claim. (Cl. 176—122)

This invention relates to electric gaseous discharge devices and more particularly to a discharge device in which the switch for pre-heating the filamentary electrode thereof is enclosed in said device.

An object of this invention is to obtain an electric gaseous discharge device which will be as compact and as self-contained as possible with respect to the auxiliary equipment necessary for the operation thereof.

Another object is to provide discharge device, such as a fluorescent lamp with the filament pre-heating means located within the lamp.

Other objects, advantages and features will be apparent from the following specification taken in conjunction with the accompanying drawing in which:

The figure shows the discharge device of my invention with a circuit therefor shown schematically.

The sealed glass envelope 1 has the lead-in wires 2 and 3 sealed in the stem 4. The filamentary electrode 5 is suspended between the top of the lead-in wire 3 and the dummy lead-in wire 6. The bimetallic strip has one end thereof attached to the lead-in wire 2 while the other end with the contact 8 thereon, is located near the dummy lead-in wire 6. The lead-in wire 3 is connected to the battery 9 or some source of electrical energy, through the resistance 10, while the lead-in wire 2 is connected thereto through the manual switch 11 with the contact 12 thereon. The voltage of the source 9 should be sufficient for striking an arc between the electrodes 5 and 8, for example, 25 volts would be satisfactory in some cases.

As shown in the figure, the circuit through the manual switch 11 is closed, thus showing the discharge device and the elements therein in the position they assume during operation. When the discharge device is not in operation the manual switch 11 is open and the contact 8 on the end of the bimetallic strip 7 is closed with the dummy lead 6.

To start the device, the manual switch 11 is closed. The filamentary electrode 5 becomes heated by the heat conducted thereto through the lead-in wire 3. The heat from the filamentary electrode plus the heat which passes therethrough to the dummy lead-in wire 6 and thence to the bimetallic strip 7 through the contact 8 will heat the bimetallic strip 7 sufficiently to cause the strip 7 to bend away thereby breaking its contact with the element 6. The filamentary electrode 5, the bimetallic strip 7 and

the lead-in wires 2 and 3 are so spaced that the bimetal will break contact at the moment the electrode 5 has become sufficiently heated to carry the discharge. When this takes place, an arc discharge will be set up between the filamentary electrode 5 and the lead-in wire 2, the filamentary electrode 5 serving as the cathode and the lead-in wire 2 serving as the anode. The discharge will generate sufficient heat to prevent the bimetal from re-establishing contact with the wire 6.

The advantages of an electric discharge device of this structure are many. For example, a two-contact fluorescent lamp may be obtained by 15 coating the walls of the glass envelope 1 with a layer of luminescent material 13. The ability to obtain a fluorescent lamp with only two contacts, both being on the same end of the lamp, is highly advantageous for it has long been desirable in many types of installation where 20 comparative small bulbs using a minimum of space is essential.

This device is designed primarily to operate 25 on direct current. A filling of an inert gas, for example argon, at very low pressure and a small amount of mercury 14 may be introduced into the lamp. However, better diffusion of the discharge is obtained if the argon pressure is less 30 than 1 mm. and in some cases the lamp may operate with a more uniform glow with no inert gas at all and only a filling of mercury vapor. The filamentary electrode is coated with one of the well known electron-emissive materials, such 35 as barium, strontium, etc.

What I claim is:

An electric gaseous discharge device comprising: a sealed glass envelope; a pair of lead-in wires sealed in one end only thereof and extending well into said envelope, with one of said wires forming an anode; a support sealed in said envelope end adjacent the other of said wires and having a contact portion; a filamentary cathode mounted between the outer end of said 40 other of said wires and said support; a bimetal member mounted on the outer end of said anode and extending toward the contact portion of said support; and a contact on said bimetal adjacent said support contact; said contacts, when 45 said device is unenergized, being closed to form a series circuit between said lead-in wires including said cathode, said contacts and said bimetal member.

HENRY J. McCARTHY.
